UNITED STATES PATENT OFFICE

DENIS F. O'BRIEN, OF EAST ORANGE, NEW JERSEY

VALVE-INSERTING METHOD AND MECHANISM

Application filed July 18, 1925. Serial No. 44,494.

This invention relates to improvements in methods of and mechanisms for inserting valves in pipes or mains under pressure and without stopping the flow of the water or other liquid therethrough, an improved apparatus of this kind being shown in my prior Patent 1,174,342, dated March 7, 1916. For brevity "pipe" will be used hereinafter as including mains.

- 10 The apparatus shown and described therein, which illustrates with substantial correctness the valve inserting method and mechanism in use prior to my invention, embodies a casing split longitudinally into upper and 15 lower sections and temporarily applied to the pipe where the valve is to be inserted and the upper one of which has an opening at which a dome is secured to it, this dome having a removable top. In this dome top there 20 is mounted a pipe cutting mechanism which during the cutting operation projects into the casing with its cutters engaging the pipe, and after such operation is completed this cutting mechanism is withdrawn from the 25 casing and into the dome, carrying with it the cut section of pipe. Communication between the casing is then closed and the dome is then cut off by a gate, the dome top is removed and the cutting mechanism and section 30 of cut pipe removed from the dome. The valve and the means for supporting it and moving it from the dome into the casing are then inserted in the dome, such supporting and moving means being mounted in the 35 dome top, which is returned to the dome. The gate before referred to is then opened and the valve moved into the casing and between the cut ends of the pipe. Then, after adjusting the valve longitudinally and 40 transversely of the pipe, with a water tight connection between it and the cut ends of the pipe, the casing is removed, the upper section thereof with its dome being preferably removed first, the space between the valve hubs 45 and pipe then calked (with lead, for example), and the lower section then removed. The means for operating the cutting mechanism and moving it out of the casing and into the dome, for moving the gate referred 50 to, and for moving the valve into the cut out

portion of the pipe and adjusting it there, are, in turn, operated by means external to the casing and dome.

The method and apparatus provided by the present invention differ in many important respects from those described in my said patent. Some of the principal differences will be briefly stated here in connection with the apparatus itself.

The temporary casing of my prior patent is dispensed with and there is used, for the performance of its functions, as well as others not performed by it, a horizontally arranged valve body which is permanently applied to the pipe so as to enclose it and also enclose the cutting mechanism previously applied to the pipe and to support the latter during the completion of the operation.

This valve body has an open end which projects beyond the pipe into suitable position for the reception of a temporary, horizontally arranged casing carrying means for operating the cutting mechanism and into which the severed section of pipe and with it the cutting mechanism are withdrawn after the pipe cutting operation, this casing being provided with means for supporting and guiding the cutting mechanism during its withdrawal.

After such withdrawal this casing is removed and a valve dome carrying a pair of valve disks and trimmings is secured to the open end of the valve body. Before the temporary casing can be removed, however, the open end of the valve body, or communication between the valve body and this temporary casing, must be closed to shut off passage of water from the pipe to the atmosphere through the valve body. For this purpose the valve body has mounted on it a temporary dome projecting upwardly from it and provided with a gate movable downwardly and upwardly into and out of a vertical aperture in the valve body near its open end. Normally, and during the pipe cutting operation and the withdrawal of the cutting mechanism from the valve body, this gate is in its upper position but when the cutting mechanism is withdrawn from the valve body it is lowered into the aperture in the valve body, thus closing the open end of the latter. The tempo-

rary casing (then containing the cutting mechanism) may then be detached from the valve body and the valve dome secured to the latter without shutting off the pressure in the pipe.

The temporary dome containing the gate is then removed from the valve body but, as this dome is in communication with the interior of the valve body and pipe, this cannot be done without previously shutting off the pressure in the pipe unless means be provided, as in the present case, to render this unnecessary. The means here provided consists of a sliding plate suitably guided and supported on the valve body and movable horizontally into and out of closing relation to the aperture in the valve body into and out of which the gate just referred to is vertically movable to open and close communication between the valve body and the temporary casing carrying means for operating the cutting mechanism. When this sliding plate is moved and locked over this aperture communication is shut off between the valve body and the gate-carrying dome, so that said dome may then be disconnected from the valve body without shutting off the pressure in the pipe.

It will thus be seen that all the operations concerned with the insertion of the valve in the pipe are completed without shutting off the pressure in the latter.

The present invention embodies other features of construction and arrangement of parts, including valve seats adjustably mounted on the valve body so that they may be adjusted longitudinally of the pipe beyond its rough ends where the pipe section has been removed, thus avoiding contact between the faces of the valves and such rough ends.

In the accompanying drawing illustrating a preferred embodiment of the present improvements—

Figure 1 is a cross section of a pipe having applied to it a cutting mechanism and a horizontally arranged valve body enclosing the pipe and also enclosing and supporting the cutting mechanism, this valve body having an open end projecting beyond the pipe and to which a temporary casing is applied containing means for operating the cutting mechanism and for withdrawing it and the severed section of pipe from the valve body into said casing, the valve body being also provided with a temporary dome having a vertically movable gate for opening and closing communication between the valve body and said casing and with means for closing communication between the valve body and the gate carrying dome,

Figure 2 is a horizontal section taken on the line 2—2 of Figure 1,

Figure 3 is a cross section similar to Figure 1 but with the open end of the valve body closed, by means of a vertically movable gate and with the casing carrying the pipe cutting

mechanism removed and replaced by the valve dome carrying the valve disks and trimmings, the valve disks being shown, by dotted lines, as slightly advanced across the faces of their seats in the valve body,

Figure 4 is a horizontal section on the line 4—4 of Figure 3, with the valve members moved to closing position,

Figure 5 is a cross section showing the valve dome on a slightly enlarged scale and with its valve disks slightly advanced across the faces of their seats in the valve body,

Figure 6 is a detail view, in vertical section and partly broken away, of a gate for closing the open end of the valve body after the withdrawal therefrom of the cutting mechanism and severed pipe section and while the casing carrying the pipe cutting mechanism is being removed and until it is replaced by the valve dome,

Figure 7 is a vertical section also on an enlarged scale illustrating the aperture in the valve body through which this gate moves and also a plate for covering this aperture when this gate and the dome in which it is mounted are removed from the valve body,

Figure 8 is a plan view of this plate and also a guiding frame in which it is moved to and from closing position, together with the means for so moving it, and

Figure 9 is a detail on an enlarged scale of a portion of one of the valve seats in the valve body.

Referring to said drawings A represents the valve body, which is mounted on and partially surrounds the pipe to which the valve is to be applied. 66 hereinafter described is the valve dome. The valve body and dome when connected constitute the valve casing.

The valve body is preferably in two parts, 1, 2, secured together by bolts 4 passing through flanges 3, and is of a length sufficient to not only span the section 5 which is to be severed from the pipe but to also extend back of the severed ends 6, 7, of the pipe so as to receive suitable packing 7' between it and the pipe and to carry and support, among other things, the valve seats and the mechanism (later described) for moving said valve seats lengthwise of the pipe and adjusting them to proper position with relation to the cut ends thereof and the valve disks in casing 66.

The part 2 of the valve body A is open at one end, to one side of the pipe, and at this open end, which projects beyond the side of the pipe, it is provided with a flange 8 for temporarily receiving a casing 9 carrying the means for operating the pipe cutting mechanism and which is provided with a flange 10 secured to flange 8 by bolts 11, and also receiving the valve dome 66.

The cutting mechanism operated from casing 9 consists of a pair of geared heads 12 and 13, carried on a frame 14, the gears and frame being split, as illustrated at 15, Fig. 2,

130

to permit them to be passed around the pipe. These gear heads carry suitable cutters 16 by which the pipe section 5 is cut out of the pipe. Any desired number of cutters may be employed, two being shown in the present instance carried by each gear. For each there is provided a star wheel 16^a to which the cutter is threaded and these star wheels are turned successively, as the gear heads rotate, by engagement with a projection 16^b for the purpose of advancing the cutters into the pipe as the cutting progresses. These gear heads are rotated to effect the cutting by a pinion 17 mounted on one end of a stud 18 carried in a yoke 19 connected with the frame 14. This yoke 19 also carries a short shaft 20 having a squared end 21. Mounted on the stud 18, at the end opposite the pinion 17, is a gear 22 which meshes with a driving pinion 23 on the stud 20. The pinion 23 is driven from a shaft 24 which at its inner end has a socket to take the squared end 21 of shaft 20, so as to rotate this shaft and through it pinion 23. The shaft 24 at its other end extends through a stuffing box 25 carried in a bonnet 26 which preferably is separate from casing 9 and secured thereto so as to be water tight by draw bolts 30. This shaft outside the frame is provided with a gear 31, which meshes with a gear 32 carried on a short shaft 33 mounted in the bonnet 26, this shaft 33 being rotated by a hand crank 34, or in any other suitable manner.

By operating the handle 34 the cutter gears are rotated and the pipe section 5 may be cut from the pipe, the gears being proportioned so as to produce the required power at the cutter gears with a minimum of effort on the crank.

It will be understood that this cutting mechanism is first applied to the pipe and then operated to partly sever the pipe, that the valve body A is then applied thereto, that the valve body and casing 9 are then bolted together, that the cutting mechanism is then set into operation, and that when the section 5 has been severed thereby from the pipe, the cutting mechanism, with this cut pipe section, is withdrawn from valve body A and into casing 9 (as shown by dotted lines in Fig. 1). The casing 9 is then detached and removed from the valve body, but before this is done a gate 50 (later on more fully described) is lowered across the open end of the valve body to prevent the flow of water therefrom; this gate remaining in this closing position until the application of the valve dome 66 to said casing, as hereinafter described, when it is withdrawn.

It will thus be observed that the body A is not only a valve body but performs the additional function of supporting the cutting mechanism during the cutting opera-

tion, the means for so supporting it being referred to more in detail later on.

The means shown for withdrawing the cutting mechanism, and with it the severed pipe section 5, from valve body A and moving it into casing 9, is as follows:

The stud 18, before referred to, carries a recessed block 35 into the recess of which extends one end of a shaft 36, this shaft being secured in the recess by a nut 37. This shaft at its other end passes through a stuffing box 38 in the bonnet 26, before referred to, and beyond the stuffing box extends through a sleeve 39, the shaft being threaded for a suitable portion of its length, as shown at 40, and on this threaded portion works a hand wheel 41 having a threaded nut portion 42 bearing against the sleeve 39. By operating this hand wheel 41 the shaft 36 is moved endwise outwardly in a horizontal direction and through the connections described the cutting mechanism is withdrawn thereby from valve body A, and into casing 9, and as this cutting mechanism encloses the pipe section 5 which has been cut off, the latter will also be similarly withdrawn. The cutter carrying frame 14 carrying the geared heads is provided with guides 43 co-operating with upper and lower guiding and supporting ribs 44 formed in the interior of the valve body and, if desired, there may be provided rollers 45 running on the surface of the lower ribs 44 to facilitate the movement of the parts from the valve body.

After the cutting mechanism has been withdrawn, with the cut pipe section 5, to the position shown in dotted lines in Fig. 1, the open end of the valve body A is closed by lowering plate 50 into place against a seat in part 2 so that the casing 9 may be removed while the pipe is under pressure and the valve dome 66 carrying the valve disks and trimmings secured thereto. Plate 50 is then withdrawn to permit the movement of the valve disks across and against their seats. For effecting these operations of the gate 50 there is provided a dome 46 removably secured, by bolts 47, to a plate 48 secured in turn, by bolts 49, to the top of the part 2 of the valve body. In this dome is mounted, so as to work vertically, the closing gate 50 which is in the form of a plate dimensioned to close the open end of the valve body (see Fig. 6), this plate working through an aperture or slot 52 formed in part 2 of the valve body and the plate 48, before referred to. The gate is formed on its inner side with wedge surfaces 53 which co-operate with wedges 54 formed in the valve body to force the gate to its seat, which may be formed in the portion 2 of the valve body A in any approved manner. As shown, this seat is of Babbitt metal held in place by being poured into dove-tail re-

cesses 55. For raising and lowering it, the gate 50 is provided at its upper end with a threaded nut or projection 57 through which passes a threaded operating shaft 58, which shaft passing through a stuffing box 59 and being operated by a hand wheel 60. By turning this wheel the gate is raised or lowered as desired.

After the valve dome 66 has been applied to valve body A, as hereinbefore described, the gate carrying dome 46 is removed but, prior to its removal, it is necessary to permanently close the aperture 52, but as this dome is in communication with the valve body and the pipe, the pressure in the latter would have to be shut off unless means were provided for rendering this unnecessary, as is done in the present case. For this purpose there is provided a plate 61 which slides between the outer surface of part 2 of the valve body and the under surface of the plate 48 in a frame F (Fig. 8) whose side 63 provides an abutment or stop for the gate in its forward or aperture-closing position as shown in Fig. 7. This plate 61 may be moved into position by means of screw rods 64 working in the side 62 of the frame and operable from outside the dome 46. After the plate 61 has been moved to closing position and dome 46 has been removed, the opening of the plate 48 registering with aperture 52 may be closed by a cap 65.

After the section 5 has been cut from the pipe and removed from the valve body A, and the gate 50 closed, as hereinbefore described, the valve dome 66, carrying the valve disks and trimmings, is put in position upon, and permanently secured to, the valve body, by means of flange 67^a on the former and the flange 8 on the latter and draw bolts 68^a connecting them. It will be observed that the valve casing, consisting of the valve body A and dome 66, thus connected together, lie in a plane at an angle to the vertical, and preferably in a horizontal plane, so that it will be as far below the ground as the pipe and freezing of the valve therefore avoided.

The valve seats 67, 68 (see Figs. 2 and 3), mounted in the valve body, are in the form of split rings so that they may be put around the pipe, these rings being placed around the pipe just back of the cutting lines and each having a seating face 69 and a threaded portion 70 engaging correspondingly threaded projections in the form of internal annular flanges 71 turned inside the parts 1 and 2 of the valve body. Beyond the threaded portion 70 each ring is formed with a toothed flange 72 through which it may be rotated to move longitudinally of the pipe. These rings are so rotated by pinions 73 carried on short shafts 74 which extend through packing glands 75 and are formed with squared heads 76 by which they may be rotated by any suitable tool from without the

valve body. With this construction a very simple and easily adjustable valve seat is provided, which can be easily moved into seating position after the cut has been made. One result or advantage of this is that the valve seats may be positioned back of the lines of cut during the cutting operation to prevent any injury to them and after the cutting is completed they may be moved endwise along the pipe into the desired position to effect a proper seating on them of the valve disks.

As before stated, the valve dome 66 carries the valve disks and trimmings and after it has been secured to valve body A, the parts are in the position illustrated in Fig. 3. The gate 50 is then withdrawn into the dome 46, the slot 52 is closed, and the dome 46 removed. The trimmings in valve dome 66 include a rotatable spindle or shaft 77 which, when rotated, causes the valve disks 78, 79 to move to and from the valve body A, so as to open communication between the two cut ends of the pipe. These disks have bronze facings 80 to ensure intimate contact between them and the valve seats 67, 68, which are of similar material. Spindle 77 passes through a stuffing box 81, in the end of the valve dome 66, and into a gear casing 82 slidably supported on bolts 83 secured to a flange 84 on the dome. The end of the spindle 77 in the casing 82 is provided with a bevelled gear 85 which meshes with a bevelled gear 86 on a vertical spindle or stud 87 provided with a nut 88 through which it may be turned by a wrench or in any other suitable manner.

This spindle 77 is of sufficient length to move the valve disks 78, 79 the full extent of their opening and closing movement and, because of the space occupied by the closing gate 50, the spindle must be slightly longer than the distance required for this full opening and closing movement. To provide for this difference and at the same time allow the parts to be positioned so that the valve dome 66 may be put into position before the withdrawal of the gate 50, the bolt arrangement 83 is resorted to. As shown in Fig. 3, the gear casing 82 is at the outward limit of its movement on the bolts. After the gate 50 has been withdrawn the mechanism may be moved to the position shown in Fig. 5, in which the bracket 82 and valve disks and trimmings have been moved to the position shown in dotted lines in Fig. 3, with bracket 82 against flange 84, this movement being effected by pushing up the parts on the bolts 83 which may then be cut off, or shorter ones substituted. Preferably to ensure perfect tightness the spindle is provided with a pair of collars 89, 90, which seat respectively in the position shown in Figs. 3 and 5, in recesses 91, 92 formed in the stuffing box 81, before referred to, and when the spindle is operated the collar 90

70

75

120

125

130

prevents endwise movement of the spindle or shaft 77. Within the valve dome 66 a draw nut 93 is threaded on the spindle, this nut acting to move the valve disks 78, 79.

To effect this the disks are formed at one end with inturned ends 94 (see Fig. 4) and an opposed boss or projection 95, the nut 93 being enclosed between the ends 94 and the boss 95. As the spindle 77 is rotated the nut 93 is moved and through it the valve disks are caused to travel forwardly and rearwardly, as may be, and open or close communication between the two ends of the pipe, the rotation of the disks and nut being prevented by the valve seats and also by guiding ribs 96 formed in the dome 66 in position to engage the outer sides of the valve disks. The valve disk operating mechanism will also include a controlling mechanism which will help seat the valve disks and hold them to their seats against water pressure, this controlling mechanism being of such character that the disks may be released so that they may be moved bodily by the spindle across the faces of the valve seats to open communication between the ends of the pipes. This controlling mechanism consists of a pair of arms 97, 98, which are pivotally mounted on pins 99 carried by projections 100 from the nut 93, before referred to, so that as the nut is moved forwardly or rearwardly these arms 97 and 98 are moved therewith. These arms are provided with inclined toes 101, which co-operate with inclined projections 102 formed on the inner walls of the valve body A, before referred to, in the path of the movement of the arms 97 and 98 which tend to engage and force said arms inwardly toward each other as they move forwardly.

At their lower ends and approximately in line with their pivot points, each of the arms 97 and 98 is provided on opposite sides with inclined members 103 which co-act with correspondingly inclined projections 104 formed on the inner faces of the valve disks 78 and 79, before referred to, so that in whatever position the arms may assume when swinging inwardly by engagement of toes 101 with inclined projections 102, the inclined members 103 will always have a broad bearing engagement with the inclined projections 104, the result of this being to secure a sliding movement of the valve disks to their seats and to ensure seating of the disks against tendency of water to open them.

If desired, stops, as threaded screws 105, may be provided passing through the part 1 of valve body A against which the edges of the valve disks contact, these stops being set to cause the forward movement of the disk to cease when they are in proper relation with their seats.

Furthermore, as these valve disks are very heavy, rollers 106 may be provided for easily

guiding the disks to and from opening and closing position, these rollers being carried on brackets 107 depending from the valve disks.

It will thus be seen that a very simple and efficient construction has been provided for inserting a valve in a pipe in which all the operations of cutting the pipe, inserting the valve and removing temporary casings are effected without shutting off the flow or in any other way interfering with the pressure in the pipe, the valve body A being positioned so that it is on a level with the pipe, thus permitting it to be of sufficient depth under ground to prevent freezing, and so that it may be put in position without leaving an obstruction above the pipe or ground. It will also be observed that during the cutting operation the cutting mechanism is supported by the valve body itself and also that while the cutting mechanism is being withdrawn from the valve body into the temporary casing containing the means for operating it, it is supported and guided by suitable means for the purpose provided in the valve body and in said casing. It will also be observed that by reason of the provision in the valve body of the seats adjustable lengthwise of the pipe all danger of contact between the faces of the valves with the rough ends of the severed pipe is avoided which in turn avoids injury to the valves.

While the invention has been shown and described in its preferred embodiment, it will be understood that various changes may be made in the specific construction, arrangement and method of operation of the parts, and that the invention is not to be restricted to the precise construction and arrangement shown and described.

What I claim is:

1. The method of inserting valve mechanism in a pipe without shutting off the flow of fluid therein including the steps of applying a rotary pipe cutter to said pipe to cut a section transversely therefrom, permanently securing to said pipe a valve body having an open end projecting in a substantially horizontal direction beyond the side of the pipe and provided with endwise adjustable valve seats, temporarily applying to said valve body a vertically arranged dome bearing a gate movable across the open end of the valve body in an aperture near the end thereof, also temporarily applying to said valve body a casing in substantial horizontal alignment therewith and having mechanism for rotating the cutter and outside means for operating said mechanism, rotating the cutter around the pipe to cut a section of the pipe, removing the cutter and cut pipe section from the valve body and into said casing, moving the gate aforesaid across the open end of the valve body to temporarily close it, removing the casing containing the

cutter rotating mechanism, permanently securing to the open end of the valve body in substantial horizontal alinement therewith a dome bearing a pair of valve disks and trimmings and means projecting therefrom for moving said disks and trimmings into the valve body and for moving said disks to and from the valve seats in the valve body, adjusting the valve seats relatively to the 10 cut ends of the severed portion of the pipe and to their respective valve disks, withdrawing the temporary gate aforesaid from the aperture aforesaid, applying permanent closure means to the outer end of said aperture, and removing the dome bearing said gate.

15 2. The method of inserting valve mechanism in a pipe without shutting off the flow of fluid therein, including the steps of applying to the pipe a rotary pipe cutter to sever a 20 section transversely therefrom and a horizontally arranged open-ended valve body provided with valve seats and projecting beyond the side of the pipe and provided with a vertical gate aperture near its open end, bolting to said valve body a horizontally arranged casing opening into said valve body and carrying means for rotating the cutter and withdrawing it and the severed pipe section from the pipe after the cutting operation, mounting on the valve body a vertically 30 arranged gate-carrying dome provided with a gate movable into and out of said gate aperture, rotating the cutter around the pipe to sever a section of pipe, withdrawing the 35 cut pipe section and cutter from the valve body and into said casing, moving said gate into the aperture aforesaid to close the open end of the valve body, removing said casing, securing to the open end of the valve body in substantial horizontal alinement therewith a dome opening into said valve body and bearing a pair of valve disks and 40 equipped with means for moving them into the valve body and to and from the valve seats therein, withdrawing the gate aforesaid from the aperture in the valve body, applying permanent closure means to said aperture, and removing the gate-carrying dome from the valve body.

45 3. In an apparatus for inserting valve mechanism in a pipe, the combination with a horizontally arranged valve body enclosing the pipe and having an open end, of a rotary pipe cutter within the valve body and rotatable around the pipe to sever a section therefrom, a casing bolted to the open end of the valve body and provided with means for rotating said cutter and withdrawing it and the severed action of pipe from the valve body 50 and into the casing, and means in the valve body and casing above and below the cutter for engaging and supporting it during the cutting operation and for supporting and guiding it and the severed pipe section during 55 their withdrawal from the valve body.

4. In an apparatus for inserting a valve in a pipe without shutting off the flow of fluid therein, the combination with a horizontally arranged valve body having valve seats and an open end projecting beyond the side of the pipe, of a rotary pipe cutter temporarily applied to the pipe within said casing and rotatable around the pipe to sever a section therefrom, a removable casing temporarily bolted to and communicating with said valve body and bearing devices for rotating said pipe cutter and for withdrawing into itself the cutter and severed pipe section, a horizontally arranged dome for permanent connection with said valve body on the removal of said casing, said dome bearing valve disks and means for moving them into the valve body and to and from the valve seats therein, said valve body being also provided with a vertical aperture near its open end and with a vertically arranged removable dome having a gate movable into and out of said aperture to close the open end of the valve body to permit the removal of said casing from and the connection of said valve dome with the valve body without shutting off the flow in the pipe, and means for permanently closing said aperture to permit the removal of the gate carrying dome without shutting off the flow in the pipe.

In testimony whereof, I have hereunto set my hand.

DENIS F. O'BRIEN.
